UNITED STATES PATENT OFFICE.

FRANK W. REED, OF LOS ANGELES, CALIFORNIA.

TONE ARM FOR SOUND-REPRODUCING INSTRUMENTS.

Application filed May 21, 1925. Serial No. 31,816.

This invention relates to improvements in sound amplifiers for sound reproducing instruments, and is particularly adapted to be used in connection with radio receiving sets.

8. An object of this invention is to provide an improved form of amplifier which is so constructed as to amplify the sound without distortion, and that the device may occupy a minimum amount of space.

10. A further object of the invention is to provide an improved amplifier formed of a conduit which has interior diameters gradually increasing from one end to the other, and which is so arranged that the device 15 cannot be easily tipped over.

With the foregoing and other objects in view which will be made manifest in the following detailed description and specifically pointed out in the appended claims, reference is had to the accompanying drawings for an illustrative embodiment of the invention, wherein:

Figure 1 is a perspective view of the improved amplifier or tone arm,

25. Fig. 2 is a front elevation of the device, parts being broken away, which may be considered as taken in the direction of the arrow 2 upon Fig. 1, and

30. Fig. 3 is a vertical section through the device taken upon the line 3—3 of Fig. 2.

Referring to the accompanying drawings wherein similar reference characters designate similar parts throughout, the improved amplifier consists of a base 10, on which is placed the conduit 11. The conduit 11 has interior diameters gradually increasing in size from the end 12 to the other end 13.

35. It is reversely bent upon itself, as indicated at 14, to provide a small portion 15 and a large portion 16, which have their axes substantially parallel and extending vertically upward from the base 10. As the taper of the conduit 11 is constant throughout, it will be appreciated that the parallel axes of the

40. portions 15 and 16 enable the adjacent sides of the portions 15 and 16 to be parallel. In the preferred form of construction, a web 17 connects the adjacent sides of the portions 15 and 16.

45. The upper end of the portion 15 is laterally bent, as indicated at 18, and is adapted to receive any conventional type of radio unit 19. The upper end of the portion 16 is forwardly bent and is provided with a bell

50. 20. In the preferred form of construction, this bell is rectangular in cross section and is

preferably formed of wood. It is secured to the portion 15 of the conduit 11 as by screws 21, although in some instances the bell 20 can be formed integral with the conduit 11. In either event, the conduit 11, the reinforcing web 17 and the base 10 are preferably formed of a single integral casting, preferably of aluminum, although other materials can be employed.

By considerable experimentation I have found that an amplification of sound from a radio unit depends upon the size and length of the conduit. The dimensions of the improved form of amplifier therefore play an important part in its construction, as a variation of size will produce distortion. I have found that in order that the amplifier will clearly amplify the sound, the upper end 12 of the portion 15 should have its interior diameter approximately three-quarters of an inch, whereas the upper end 13 of the portion 16 should have its interior diameter substantially three inches. The interior length of the conduit 11 should be substantially twenty-four inches. By making the conduit with such dimensions, an amplification of sound is possible without distortion. Furthermore, if a greater taper or a smaller taper is used upon the conduit, the amplification will be such as will not produce a proper clear tone reproduction of the proper pitch. It will be noted that as both portions 15 and 16 are arranged directly above the center of the base 10, that the center of gravity of the device is substantially over the center of the base, and that the device cannot be easily tipped over. Furthermore, as both portions 15 and 16 are arranged side by side, because of the reverse bend 14 being positioned upon the base, the device occupies a relatively small amount of space, but at the same time allows the required size or length of conduit to be used.

From the above it will be appreciated that an improved form of amplifier or tone arm is provided, which is not only so constructed as to occupy a small space, but which will properly amplify sounds from a radio unit and is of an attractive appearance.

It will be understood that various changes in the detail of construction may be made without departing from the spirit or scope of the invention as defined by the appended claims.

I claim:

1. A device of the class described com-

- prising a single casting providing a base, a conduit reversely bent to provide parallel portions and having its bend on the base and its two parallel portions extending upwardly therefrom, a web connecting the parallel portions of the conduit, said conduit having its internal diameter gradually increasing from one end to the other, and means providing a bell upon the enlarged 10 end of the conduit.
2. A device of the class described comprising a tubular conduit having its interior diameter gradually increasing in size from one end to the other, the conduit being reversely 15 bent upon itself so that the axes of the two reversely bent portions of the conduit are substantially parallel, and means providing an integral base for the device at the mentioned bend in the conduit.
- 20 3. A device of the class described comprising a base, a tubular conduit having its interior diameter gradually increasing in size from one end to the other, said conduit being reversely bent upon itself, with the 25 bend positioned upon the base, the portions of the conduit extending upwardly from the base and having their axes substantially parallel, and means providing a laterally extending bell upon the enlarged end of the 30 conduit.
4. A device of the class described comprising an integral casting providing a base, a reversely bent conduit upon the base with its bend on the base, the portions of the conduit extending upwardly therefrom with 35 their axes substantially parallel, the interior of the conduit having diameters gradually increasing in size from one end to the other, and means providing a laterally extending bell upon the enlarged end of the conduit, 40 the bell extending over the reduced end of the conduit and the reduced end of the conduit having its upper end bent laterally from beneath the bell.
5. In a device of the class described, a tubular conduit reversely bent upon itself, the interior of the length being approximately twenty-four inches long, and the interior size of the conduit gradually increasing from approximately three-quarters of an inch in 45 diameter at one end to approximately a three inch diameter near the other end.
6. In a device of the class described, a tubular conduit reversely bent upon itself, the interior of the length being approximately twenty-four inches long, and the interior size of the conduit gradually increasing from approximately three-quarters of an inch in diameter at one end to approximately a three inch diameter near the other end, and 50 means providing a laterally extending bell upon the large end of the conduit.

In testimony whereof I have signed my name to this specification.

FRANK W. REED.
